CHARLES W. DIFFENDERFER, OF GREENCASTLE, PENNSYLVANIA, ASSIGNOR TO THE
INTERWOVEN MILLS, INC., OF NEW BRUNSWICK, NEW JERSEY, A CORPORATION
OF NEW JERSEY

CIRCULAR-KNITTING MACHINE

Application filed July 20, 1928. Serial No. 294,216.

This invention relates to circular stocking knitting machines and more particularly to an improvement in that type of machine commonly known in the art as the split-foot machine, generally illustrated in the Hemphill Patent 933,443 and known to the trade as the Banner machine, which in addition to the parts disclosed in said patent carries a stiper attachment for producing a horizontally striped sock. The present invention is essentially designed as an improvement on the construction disclosed in the application of Joseph Haas and Russell Evans, filed November 14, 1927, Serial No. 233,145, wherein there is illustrated an improvement on the Banner machine designed to place upon the upper section of the toe pocket a reinforcement in the nature of a plating which was designed so as to avoid a bulky gore line and thereby prevent unpleasant irritation to the tender skin at the side of the great toe. As explained in the aforesaid Haas and Evans application, stockings of this type, whether seamless or full-fashioned, carry a line of what are termed selavage stitches at each side of the toe pocket which join the upper and lower sections of said pocket which being constructed of relatively heavy thread produce a gore line of considerable thickness which irritates the tender skin at the side of the great toe. If this gore line is increased in bulk the irritation would undoubtedly result in considerable discomfort to the wearer which has been wholly avoided by constructing the reinforce or plating panel in such manner that it does not extend to the gore line on either side of the toe pocket back of the point normally engaged by the great toe nail, so that these gore lines are not increased in bulk and yet the reinforce extends over a sufficient area to properly protect the stocking against the wear produced by the constant rubbing of the sock against the shoe cap.

The Haas and Evans machine disclosed in the above identified application, while being capable of placing the peculiar shaped reinforce disclosed in Mettler, Haas and Evans application filed September 24, 1927, Serial No. 221,666, it has been found out that when the machine is operating under power fre-

quently the yarn finger feeding the plating yarn to the needles is withdrawn a little too early which causes the production of a reinforce or plating panel having an uneven and ragged appearance. This fault in the Haas and Evans machine does not affect in any way the strength or wearing properties of the reinforce, but does produce, as before stated, an uneven edge which materially affects the appearance and selling qualities of the stock.

It is, therefore, the principal object of this invention to avoid the difficulties which have been encountered in the Haas and Evans machine and to provide mechanism which insures the introduction and withdrawal of the plating thread at the same point in all courses in which said plating thread is introduced, thereby producing a reinforcing panel having clean-cut marginal edges which show no unevenness.

Further objects of the invention will appear as the following specific description is read in connection with the accompanying drawings which form a part of this invention, and in which

Fig. 1 is a side elevation showing my invention applied to a circular knitting machine of the Banner type;

Fig. 2 is a side elevation taken from a point opposite to that in Fig. 1, with parts of the side plate of the machine broken away to better illustrate the features of this invention;

Fig. 3 is a detail elevation of certain portions of the knitting mechanism illustrating parts disclosed in Fig. 2 on an enlarged scale;

Fig. 4 is a skeleton rear elevation;

Fig. 5 is a detail section showing the yarn fingers and their operating connections;

Fig. 6 is a detail horizontal section taken on the line 6—6 of Fig. 1;

Fig. 7 is a perspective view showing in detail the connection of one of the pattern levers with the pull rod or wire;

Fig. 8 is a detail front elevation showing the improved double-sole lever;

Fig. 9 is a side elevation of said lever;

Fig. 10 is a sectional view taken on the line 10—10 of Fig. 8;

Fig. 11 is a similar sectional view showing the cam block of the double-sole lever shift-

ed to one side of its normal position by the high splice cam;

Fig. 12 discloses a modification of the high splice cam for accomplishing a purpose similar to that obtained by the shifting of the cam block on the double-sole lever; and

Fig. 13 is a perspective view of the double-sole lever showing a modified type of spring for actuating the cam lug arm or lever.

For the purpose of obtaining a complete understanding of the operation of the improved double-sole lever, it is necessary to describe in part the features of the Banner machine which cooperate to produce the operation and proper control of the improved double-sole lever and hence the description found in the Haas and Evans application above identified is repeated here.

The Hemphill Banner machine as generally illustrated in the Hemphill Patent 933,443 comprises a base plate 1 which is supported upon legs 2 and has rising therefrom a pair of side plates 3 and 3^a supporting a top 4 upon which the knitting head 5 is carried. Journalled in suitable bearings in the side plates 3 and 3^a is what is known as the pattern shaft 6 having connected thereto the customary ratchet wheel 7 operated intermittently by mechanism not disclosed herein through the 104-tooth gear shown at 8. The shaft 6 also carries the sprocket 9 over which the pattern chain 10 is adapted to travel in the usual manner and this pattern chain throws, by means of lugs on its links, certain pawls one of which is illustrated at 11. This pawl, where the Banner machine has a stiper attachment applied thereto, is connected by means of a link 12 to a lever 13 pivoted at 14 to the side plate 3. The rear end of this lever is connected by means of a link 15 to the pattern chain pawl holder 16 which as shown in Fig. 4 is substantially L-shaped. This pawl holder is freely pivoted upon the stiper pattern shaft 17 and has its upper right-angular end extended horizontally over the pattern chain sprocket 18 and over the pattern disc shaft ratchet 19 as shown in Fig. 4.

Pivoted on the side plate 3 which supports the lever 13 is the pattern chain pawl 20 having its rear end formed into a chain engaging foot 21 which is adapted to rest upon the stiper pattern chain 22 when released as will be hereinafter described. This pawl 20 is supported in elevated position by the pawl holder 16 but immediately upon being released by such pawl holder is forced into engagement with the pattern chain 22 by a contractile spring 23 which is also connected to the rear end of the lever 13 and serves to return the pawl holder and lever 13 to their normal positions as illustrated in Fig. 1.

Pivoted to the under side of the top 4 is a depending link 24 which carries the pattern chain pawl 25 adapted to ride idly over the

ratchet wheel 19 in one movement and to engage and rotate said ratchet wheel in the opposite movement. The link 24 is engaged with the pawl holder 16 and when this latter part is in its normal position shown in Fig. 1, the link 24 is held out of the path of a roller stud 26 secured eccentrically to the inner side of the 104-tooth gear 8. When, however, the pawl holder 16 is retracted by the elevation of the pawl 11 and the depression of the rear end of the lever 13 against the tension of the spring 23, the link 24 will be drawn forwardly by the action of the spring 27, connected at one end to the link 24 adjacent its upper end and at its opposite end to the inner side of the side plate 3 so as to bring the link 24 within the path of the eccentric roller stud 26. This roller stud then camming upon the link 24 and forcing the same rearwardly causes the pawl 26 to engage and rotate the ratchet 19 which is keyed as shown in Fig. 4 to the stiper pattern shaft 17.

All of the foregoing mechanism is a part of the usual Banner machine with horizontal stiper attachment and forms no part of this present invention except as it cooperates with the elements which will now be described.

Projecting inwardly from the side plate 3^a is a stud 28 upon which is pivoted a pair of levers 29 and 30 each of which is adapted to bear at its rear end upon the pattern disc 31 which in this instance is shown as supplied with three sets of cams as particularly shown in Fig. 3 and each set consisting of cams 32 and 33. Each cam 32 is adapted to elevate the rear end of the lever 29 while each cam 33 is adapted to elevate the rear end of the lever 30.

The lever 29 is extended into the machine toward the forward end thereof and has connected to its inner end a wire or link 34 which extends upwardly through the top 4 and into the yarn change lever bracket 35 where it is connected at its upper end to a yarn change lever 36 pivoted to the bracket 35 as particularly shown in Fig. 5. This lever has its forward end bearing upon the under side of a yarn finger 37, as is customary, which finger is acted upon by a spring 38 to normally throw it into operative yarn feeding position, but is held out of operative position by the yarn change lever 36 until the rear end of said lever is elevated so as to release the finger 37 to the action of the spring 38.

The lever 30 has connected to its front end a rod 39 pivoted at its upper end to the horizontal arm of a bell crank lever 40 pivoted at 41 to a bracket 42 depending from the top 4. The vertical arm of this bell crank lever is bifurcated as shown to receive a laterally extending stud 43 carried upon a sleeve 44 slidably mounted upon a shaft 45 secured in bearings 46 depending from the top 4. The sleeve 44 is normally thrown to the left in Fig. 4 by means of a spiral spring 47 sur-

rounding the shaft 45 between the bearing 46 and the end of the shaft. This spring 47 as shown particularly in Fig. 8 has one terminal secured to the bearing 46 and its opposite end secured to the sleeve 44 so that in addition to acting as a compression spring to normally throw the bell crank or double-sole lever 40 out of the path of the high splice cam it also acts as a torsion spring for a purpose which will be clearly understood from what follows.

The sleeve 44 carries at one end an arm 48 provided with a lateral extension 49 arranged in the path of an adjusting set screw 50 threaded into the top 4. The terminal of the arm 48 has secured thereto a rod 51 which extends upwardly into the yarn change bracket 35 and is connected at its upper end to the lever 36 as clearly shown in Fig. 4. The opposite end of the sleeve 44 has formed integrally therewith a lug 52 into which is threaded an arm 53 which is threaded at its outer terminal as shown at 54 to receive an adjustable stop 55 which is held in position on the arm 53 by means of a lock nut 56. Adjacent the lug 52 there is also adjustably secured a stop collar 57, the purpose of which will be understood as the description proceeds.

Slidably mounted upon the arm 53 is a lug 58 having the face adjacent the rear of the machine provided with a V-shaped notch 59 presenting cam surfaces 60 which are engaged by a roller 61 journaled on a shaft 62 secured in the spaced arms of a combined guiding and clamping lever 63. This lever as shown in Figs. 8, 10 and 11 comprises a pair of spaced arms 64 and 64^a joined by a bridge piece 65. As disclosed the arms 64 and 64^a straddle the lug 52 and receive a pivoting pin 66 which is held in position by a U-shaped retainer 67 passing through the arms of the lever and engaging the bifurcated ends of said pin.

As shown the arms 64, 64^a of the lever 63 straddle that portion of the lug 58 which carries the V-shaped notch 59 and the roller 61 is pressed into engagement with said notch by means of a substantially U-shaped spring 68 which is clamped to the lug 52 by a set screw 69 and is reinforced by a thin leaf spring 70 held in position above the spring 68 by the set screw 69. This reinforcing spring is as noted in Fig. 10, tapered from its butt end to the lower terminal thereof so that it gives readily with the spring 68 and prevents the same from having any definite point of flexing as would be the case were the spring 68 held against the lug by a washer and clamp nut. As shown the spring 68 has its lower terminal or yoke end bent at right-angles and contacting with the bridge 65 of a lever 63 and with the leaf spring 70 normally tends to force the roller 61 into the bottom of the notch 59.

The lug 58 has its face opposite to the notch 59 provided with bevelled surfaces 71

arranged to be engaged by the shoulder rises 72 on the high splice cam 73. This high splice cam as shown is keyed to a shaft 74 and is reciprocated through mechanism driven by the 104-tooth gear 8 as is customary during reciprocating knitting, and has high and low spots indicated at 75 and 76 respectively, the high spot of the cam being extended throughout the major portion of the circumference and the low spot being divided into two parts 75 as is clearly shown in Fig. 11. The cam as usual is in the form of a split ring its ends being connected together by a screw 77 thus producing a gap which the lug 58 would enter were it not for the fact that the arm 53 is 80 limited in its inward movement toward the shaft 74 by the extension 49 coming into engagement with the adjusting screw 50.

In the operation of the device as thus far described when the pawl 11 is raised by a lug on the pattern chain 10 the forward end of the lever 13 will be elevated and its rear end depressed against the tension of the spring 23. This depression of the rear end of the lever 13 will throw the link 15, pull the pawl holder to the position shown in dotted lines in Fig. 1, and thus permit the pawl 20 to drop onto the chain 22. The retraction of the pawl holder 16 also releases the link 24 which is then drawn into the path of the eccentric stud 26 in the 104-tooth gear and is thus reciprocated back and forth by said stud so long as the pawl holder 16 remains retracted, the pawl holder being held in retracted position by a notch 21^a formed on the under side of the pawl.

The rearward movement of the link 24 as actuated by the stud 26 will cause a rotation of the shaft 17 so long as the pawl 20 remains in engagement with the pattern chain 22. 105 When, however, a lug link on the pattern chain is brought into engagement with the depending foot 21 of the pawl 20 this pawl is then elevated which frees the pawl holder from the locking notch and thus permits the spring 23 to restore said pawl holder to its normal position as shown in full lines in Fig. 1. This movement of the pawl holder carries the link 24 out of the path of the stud 26 and no further rotation of the pattern shaft 17 will occur until another lug on the pattern chain 10 is brought into engagement with the pawl 11.

During the normal knitting of the leg, foot and toe and under portion of the toe of the stocking, the lever 29 has its rear end resting upon one of the cams 32 and elevated above the surface of the disc 31. This causes the inner end of the lever 29 to be depressed so that the forward end of the yarn change lever 36 is held elevated and the yarn finger also elevated so as to keep the yarn carried thereby out of the path of the needles. When a lug on the pattern chain 10 lifts the pawl 11 and through the mechanism just described

the pattern shaft 17 is rotated, the disc 31 is moved in the direction of the arrow in Fig. 3 so as to carry the cam 32 which has been supporting the rear end of the lever 29 out of engagement with such lever. This permits the spring 38 to throw the particular yarn finger down into the position shown in dotted lines in Fig. 5 and elevate the forward end of the lever 29 through the lever 36 and link 34. Thus the yarn carried by the finger 37 is drawn into the path of the needles and is maintained in such position so long as the rear end of the lever 29 rests upon the surface of the pattern disc 31.

15 When the rear end of the lever 29 is again elevated the yarn finger 37 is thrown out of operation through the depression of the forward or inner end of the lever 29 and the elevation of the forward end of the yarn change lever 36.

As before explained the spring 47 normally forces the sleeve 44 to the left as viewed in Figs. 4 and 8 so as to throw the arm 53 out of the path of the high splice cam 73. This is the position of the parts when the rear end of the lever 30 is raised upon the periphery of the pattern disc 31. When, however, the pattern disc has been rotated a sufficient distance and the rear end of the lever 29 is raised upon the face of said pattern disc, one of the cams 33 will engage and elevate the rear end of the lever 30 thus depressing its forward or inner end, drawing down on the link or rod 39 and turning the bell crank lever 40 so as to shift the sleeve 44 against the tension of the spring 47 and bring the arm 53 and the lug 58 into the path of the high splice cam 73. As this cam reciprocates during the knitting of the toe pocket the rear end of the yarn change lever 36 will be elevated when the low spots on the cam engage the lug 58 and will be depressed when the high spot on the cam is acting upon said lug. Thus in the reciprocation of the cam 73 the yarn finger 37 is thrown into and out of operative position to feed yarn to the needles at suitable intervals governed by the number of needles in operation and by the position of the high and low spots on the cam 73.

As is well understood in the knitting of the toe pocket, a reciprocating operation, a needle is dropped with each reciprocation of the knitting head so that when the bottom 55 of the toe pocket is being knit it will be gradually narrowed to the narrowest course at which time, through the operation of the pattern control, needles will be added at each stroke so as to widen the upper portion 60 of the toe pocket out to correspond with the width of the bottom and to properly join the bottom and top portions of the toe pocket at the side gores. It is at this point of widening of the upper portion of the toe 65 pocket that the lever 30 drops off of one

of the cams 33 so that the yarn finger 37 is thrown into action immediately upon beginning the widening of the toe pocket and is continued in this manner so long as is desired, insert the plating yarn which is carried by the yarn finger 37 throughout the full width of the courses and joining them with the under-courses of the toe pocket in the selvage stitches. This operation is continued for a sufficient number of courses to carry the plating reinforcement far enough back from the tip to insure at all times reinforcement over the great toe nail. Then when ten or twelve courses have been knit in this manner, which is usually sufficient, one of the cams 33 is brought into engagement with the lever 30 and the rear end of this lever elevated so as to depress its forward or inner end, thus shifting the sleeve 44 and bringing the arm 53 into the path of the high splice cam 73. In the reciprocation of this cam its low spots 76 are presented to the lug 58 carried by the arm 53 which lug drops into such low spots by action of the springs 68 and 70. When a low spot is engaged by the lug 58 the arm 48 will be elevated with its accompanying rod 51 and the forward end of the yarn change lever will be depressed so as to permit the spring 38 to throw the yarn finger 37 into operation. When the high spot on the cam is brought into engagement with the lug 58 the arm 53 is thrown away from the shaft 74 and the arm 48 depressed with its rod 51, thus causing the elevation of the forward end of the yarn change lever and a consequent elevation of the yarn finger against the tension of the spring 38.

In the practical operation of this plating attachment when the lug 58 is arranged in the path of the high splice cam 73, the yarn finger will be thrown into and out of operation at predetermined points in each course across the upper section of the toe pocket and when the lever 29 is engaged by cam 32 on the pattern disc 31, the yarn finger 37 will feed the plating yarn to all of the needles in operation during the widening of the toe pocket so that the plating yarn will extend from gore line to gore line in each course. After the lever 29 has been released by one of the cams 32 the lever 30 will be elevated upon a cam 33 and through the link 39 and bell crank 40 will shift the sleeve 44 against the tension of the spring 47 thus placing the lug 58 in the path of the high splice cam which thereafter acts to control the position of the yarn finger 37. During the reciprocation of the high splice cam 73 high and low spots are presented to the lug 58 and the sleeve 44 consequently rocked by its shaft 45 against the tension of the spring 47 then acting as a torsion spring. This was the operation of the Haas and Evans machine disclosed in the aforesaid application and

in that machine it was intended that the yarn finger should be operated to throw the plating yarn into and out of operation on the same needle at intermediate points on either side of the center of any particular course and removed some distance from the selvage stitches as illustrated in the rectangular portion of the panel shown in application Serial No. 221,666, filed September 24, 1927 by Mettler, Haas and Evans. In the Haas and Evans machine, however, when the solid lug of the bell crank or double-sole lever was engaged by the rises of the high splice cam, said lug was either wiped out onto the high spot of the cam in proper order or was suddenly kicked out and when the latter action occurred the yarn finger was thrown out of operation sometimes two or three needles too soon so that when this occurred between normal operations, a ragged edge was produced on the plated panel and float threads appeared on the inner side of the sock. This difficulty has been entirely avoided by changing the high splice cam-engaging lug on the double-sole lever from a solid lug to a shiftable lug or sliding lug as illustrated at 58 which when engaged by either rise on the high splice cam will slide on the arm 53 causing the roller of the arm 63 to ride up on one of the inclined surfaces 60 of the notch 59 against the tension of the springs 68 and 70. This sliding of the lug 58 does not in any way affect the operation of the cam 73 but takes up the shock delivered to the lug when hit by the rise on the cam and causes the lug to move on the arm 53 until engaged by one of the stops 55 or 57 to be evenly wiped out from the low spot at the proper time, thus insuring an elevation of the yarn finger so as to remove the plating thread at the proper time. After the lug has been wiped out into the high spot the roller 61 acting upon the inclined surface 60 restores the lug to its central or intermediate position between the stops 55 and 57 as shown in Figs. 9 and 10, the springs 68 and 70 acting to accomplish this purpose.

The foregoing arrangement of parts, that is with the double-sole lever provided with a shiftable lug to be engaged by solid shoulders or rises on the high splice cam, is the preferred form and the form which I am at present using in actual practice. I find that substantially the same results may be obtained by making the cam-engaging lug on the double-sole lever integral with one arm of said lever and providing the high splice cam 73 with shoulders which give and take up any undue shock when they engage the solid lug of the double-sole lever. I have illustrated such an arrangement in Fig. 12 wherein a double-sole lever is indicated at 93 similar to that disclosed in Haas and Evans machine and is provided with a cam-engaging lug 94

arranged to be engaged by the spring pressed abutments 95 forming the rises of the high splice cam 73. In this particular instance the low spots on the cam indicated at 76 are continued for some distance to a substantially radial shoulder 96. Extending inwardly from said shoulder on a substantially tangential line is a bore 97 having fitted therein a compression spring 98 against which the inner end of the shank 99 of the abutment 95 rests. The shank 99 as shown is provided with a longitudinal slot 100 through which a limiting pin 101 extends as shown and limits the outward movement of the shank thus determining the position of the abutment when the shank is fully extended under the action of the spring.

When one of the abutments or rises 95 is brought around into contact with the lug 94 of the double-sole lever, the abutment will come to a stop and the cam 73 continuing to rotate will compress the spring 98 until the shoulder 96 is brought into engagement with the abutment 95 at which time said abutment will wipe over the inclined face of the lug 94 and push the same outwardly until the high spot on the cam 73 is reached, at which time the abutment will be released and will spring forward to its normal position and remain in such position until it re-engages the lug.

It will thus be seen that with this arrangement the shock of engagement of the rise with the lug is taken up in substantially the same manner as this result is produced by the construction disclosed in Figs. 9, 10 and 11.

In order that the rod or wire 34 will not operate the lever 29 when the high splice cam is shifting the yarn change lever, I preferably provide a loose connection between the lever 29 and the rod 34 so that upon depression of the rear end of the yarn change lever 36 the rod 34 will slide with respect to the lever 29 and will not operate the same. One form of a lost motion connection which will serve the purpose herein, is illustrated in Fig. 7, wherein the front end of the lever 29 is provided with a bifurcation 29^a adapted to receive the rod 34 and to permit said rod to freely slide in said bifurcation at certain times. The end of the rod 34 is shown as provided with a wide loop 34^a which is engaged by the lever 29 when the forward or inner end is depressed by one of the cams 32, this of course occurring when the lever 30 has its rear end resting upon the pattern disc 31 and the arm 48 of the bell crank out of the path of the high splice cam.

As shown in Fig. 4 of the copending application filed September 24, 1927, Serial No. 221,666, the reinforcement, knit into the upper panel of the toe pocket, is in the form of an arrow head while in Fig. 3 of this same application the reinforcing is made in the

form of a rectangular panel having a width somewhat less than the width of the shortest course of the toe pocket. The operation of the machine as just described covers the insertion of the plating thread to produce a panel similar to that illustrated in Fig. 4 of application Serial No. 221,666 but I wish it to be understood that by proper adjustment of the cams on the pattern disc 31 or more specifically speaking the advancement of the cams 33 on said cam disc 31 the operator may control the actuation of the lever 30 and the consequent reciprocation of the rod or wire 39 when the needles start the widening of the toe pocket and this operation can be continued as long as it is desired so as to form a rectangular panel of somewhat less width than the narrowest course of the toe pocket to produce a panel like that illustrated in Fig. 3 of the aforesaid application. In such case none of the plating threads are extended to the side gores of the toe pocket and therefore the selavage stitches are not increased in bulk at any point.

When knitting in a reinforcing or plating thread less than the width of the narrowest course the tension on the plating yarn must always be substantially the same. Under these circumstances, when the yarn finger carrying the plating thread is thrown out of operation, there would be considerable slack in the yarn between the yarn finger and the bobbin if no means were provided for taking up this slack and as a consequent result numerous float threads would be present on the inner side of the stocking which would subsequently have to be removed in the usual manner. In order to prevent these float threads I secure to the side plate 3^a a stud 78 which extends diagonally away from said side plate and has pivoted thereon a lever 79 one end of which normally rests upon the rear end of the lever 29 as shown in Figs. 2, 3 and 4. The opposite end of the lever has adjustably secured thereto a rod 80 which extends vertically and is connected through a coupling member 81 to a takeup wire 82 which is normally elevated by a spiral spring 83 surrounding said wire between a bracket arm 84 and an adjustable collar 85 secured to said wire. The bracket 80 is carried by the usual bobbin stand rod 86 which also carries the takeup bracket 87. This bracket is apertured to permit the passage of the takeup wire 82 and is provided with pivoted ears 88 between which is pivoted the usual form of takeup lever 89 in the forward end of which is formed the usual yarn guide 90. The rear end of the lever 89 is connected by a spring 91 to the bobbin stand rod 86, which spring normally acts to elevate the forward end of the lever 89 when the lever is released by the takeup wire 59.

When the lever 29 has its rear end resting upon the pattern disc 31 the contacting end

of the lever 79 will also be depressed permitting the spring 83 to elevate the takeup wire and engage the takeup lever 89 between its pivot point and the connection of the spring 91 thus operating to depress the forward end of the lever 89 against the tension of the spring 91. In this position the forward end of the lever 29 is elevated with the result that the spring 83 has thrown the yarn finger into position to feed the yarn carried thereby into the path of the needles. When the rear end of the lever 29 is elevated upon a cam 32 the contacting end of the lever 89 will also be elevated and the takeup wire pulled downwardly against the tension of the spring 83 thus carrying the upper end of said wire out of engagement with the lever 89 permitting the spring 91 to elevate the forward end of the lever 89 and thus take up the slack caused by the elevation of the yarn finger.

When the lever 29 has its rear end depressed and the rear end of the lever 30 is elevated on a cam 33 said lever 30 fits within a notch 92 formed on the under side of the lever 79 so that this lever does not interfere in any way with the operation of the lever 30 and vice versa.

In Fig. 13 I have shown a modified type of spring for actuating the arm 63 toward the lug 58 and for holding the roller 61 against the cam surfaces 59 and 60. In this form the spring is constructed of a single strand of spring wire bent upon itself so as to present a substantially U-shaped outline and is indicated generally at 68^a. The legs of said spring are bent downwardly and crossed as shown at 68^b and the terminals 68^c of said legs are straightened into parallelism and held beneath the washer 68^d by the set screw 69. As will be seen from an inspection of Figure 13 the crossing of the legs produces in that portion that is crossed a torsional action when the arm 63 is lifted by the action of the high-splice cam on the lug 58. This takes up and distributes the strength over a considerable length of the spring and prevents establishing a direct fulcrum-point where the spring is engaged by the washer 69^d.

What I claim is:

1. Actuating mechanism for yarn fingers of circular stocking knitting machines, comprising a reciprocally mounted element, operative connections therefrom to a yarn finger, means for intermittently reciprocating said element to insert and withdraw said yarn finger, and means for delaying the movement of said element during one portion of a cycle of reciprocation to insure insertion and withdrawal of the yarn finger at the same needle.

2. Actuating mechanism for yarn fingers of circular stocking knitting machines, comprising a pair of reciprocating elements one of which drives the other, connections from

one of said elements to a yarn finger to reciprocate the same, and means associated with one of said elements for delaying the action of the connections on said yarn fingers whereby said yarn finger is manipulated to insert and withdraw the yarn at the same needle.

3. Mechanism for moving yarn feeding fingers of circular stocking knitting machines into and out of operative yarn feeding position, which comprises a pair of reciprocating elements one of which drives the other, and a yielding member interposed in the drive between said elements for causing a retarded withdrawal of the yarn finger from feeding position.

4. Mechanism for reciprocating yarn feeding fingers of circular stocking knitting machines into and out of operative yarn feeding position, comprising a pair of reciprocating elements one of which drives the other, and a yielding member carried by the driven member for causing a retarded withdrawal of the yarn finger from operative feeding position.

5. Mechanism for reciprocating yarn feeding fingers of circular stocking knitting machines into and out of operative yarn feeding position, comprising a cam and reciprocable means driven thereby connected to the yarn finger, and a yielding member interposed between the cam and the reciprocable means for delaying the withdrawal of the yarn feeding finger from operative feeding position.

6. Mechanism for reciprocating yarn feeding fingers of circular stocking knitting machines into and out of operative feeding position, comprising a reciprocating connection to said finger, a reciprocating cam for operating said connection, and a yielding element interposed in the drive between the cam and said connection for relieving the connection of the shock delivered by the cam and thereby retarding movement of the connection to withdraw the yarn finger from operative feeding position until the inertia of the connection is overcome.

7. Mechanism for reciprocating yarn feeding fingers of circular stocking knitting machines into and out of operative yarn feeding position, comprising a reciprocating member, an operative connection from said member to the yarn feeding member, a reciprocating cam for operating said member, and means interposed in the drive between the cam and said member for retarding the movement of said member until the inertia of the connection and member has been overcome.

8. Means for reciprocating yarn feeding fingers of circular stocking knitting machines into and out of operative yarn feeding position, comprising a reciprocally mounted lever, a reciprocating cam for operating said lever, a connection between said lever and the yarn feeding finger constructed

to remove said feeding finger from operative feeding position when moved in one direction and to release the yarn feeding finger for movement into yarn feeding position when moved in the opposite direction, and a yielding member carried by said lever and engaged by a cam rise for retarding the throw of said lever to remove the yarn feeding finger from operative yarn feeding position.

9. Mechanism for reciprocating yarn feeding fingers of circular stocking knitting machines into and out of operative yarn feeding position, comprising a reciprocally mounted lever, a connection between said lever and yarn feeding finger constructed to throw said yarn feeding finger out of operative yarn feeding position when moved in one direction and to permit the yarn feeding finger to be moved into yarn feeding position when moved in the other direction, a sliding abutment on said lever constructed to retard the throw of the lever to move the yarn finger out of operative yarn feeding position, and a reciprocating cam arranged to engage said abutment for operating the lever.

10. Mechanism for reciprocating yarn feeding fingers of circular stocking knitting machines into and out of operative yarn feeding position, comprising a reciprocally mounted lever, a connection between said lever and yarn feeding finger constructed to throw said yarn feeding finger out of operative yarn feeding position when moved in one direction and to permit the yarn feeding finger to be moved into yarn feeding position when moved in the other direction, a sliding abutment on said lever constructed to retard the throw of the lever to move the yarn finger out of operative yarn feeding position, a reciprocating cam arranged to engage said abutment for operating the lever, and means for returning the abutment to normal position.

11. Mechanism for reciprocating yarn feeding fingers of circular stocking knitting machines into and out of operative yarn feeding position, comprising a reciprocally mounted lever, a connection from said lever to a yarn finger constructed to throw said yarn finger out of operative yarn feeding position when moved in one direction and to permit the return of the yarn finger to yarn feeding position when moved in the opposite direction, a reciprocating cam having spaced rises, and a sliding abutment carried by the lever and arranged to be moved on said lever in either direction of reciprocation of the cam by said rises for retarding the movement of said lever to withdraw the yarn feeding finger from operative yarn feeding position.

12. Mechanism for reciprocating yarn feeding fingers of circular stocking knitting machines into and out of operative yarn feed-

ing position, comprising a reciprocally mounted lever, a connection from said lever to a yarn finger constructed to throw said yarn finger out of operative yarn feeding position when moved in one direction and to permit the return of the yarn finger to yarn feeding position when moved in the opposite direction, a reciprocating cam having spaced rises, a sliding abutment carried by the lever and arranged to be moved on said lever in either direction of reciprocation of the cam by said rises for retarding the movement of said lever to withdraw the yarn feeding finger from operative yarn feeding position, and means constructed to return said abutment to normal position when moved in either direction.

13. Mechanism for reciprocating yarn feeding fingers of circular stocking knitting machines into and out of operative yarn feeding position, comprising a reciprocally mounted lever, a connection from said lever to a yarn finger constructed to throw said yarn finger out of operative yarn feeding position when moved in one direction and to permit the return of the yarn finger to yarn feeding position when moved in the opposite direction, a reciprocating cam having spaced rises, a sliding abutment carried by the lever and arranged to be moved on said lever in either direction of reciprocation of the cam by said rises for retarding the movement of said lever to withdraw the yarn feeding finger from operative yarn feeding position, and means constructed to return said abutment to normal position when moved in either direction, together with adjustable stops for limiting the movement of the abutment in either direction.

14. Mechanism for reciprocating yarn feeding fingers of circular stocking knitting machines into and out of operative yarn feeding position, comprising a reciprocally mounted lever, a connection from said lever to a yarn finger constructed to throw said yarn finger out of operative yarn feeding position when moved in one direction and to permit the return of the yarn finger to yarn feeding position when moved in the opposite direction, a reciprocating cam having spaced rises, a sliding abutment carried by the lever and arranged to be moved on said lever in either direction of reciprocation of the cam by said rises for retarding the movement of said lever to withdraw the yarn feeding finger from operative yarn feeding position, means constructed to return said abutment to normal position when moved in either direction, said abutment provided with opposed inclined surfaces, and a spring actuated roller adapted to engage either surface for retarding the movement of the abutment and returning the same to normal position.

15. A double-sole lever for circular stocking knitting machines, comprising a bell

crank lever, a sliding abutment mounted upon one arm thereof, stops for limiting the movement of said abutment in either direction, said abutment having opposed inclined surfaces, an arm spring-pressed toward said abutment, and a roller carried by said arm and arranged to ride upon said surfaces to retard the movement of said abutment and to return the same to normal position when moved in either direction.

In testimony whereof I affix my signature.

CHARLES W. DIFFENDERFER.
